(57) **CLAIM**

The ornamental design for an audio system, as shown and described.

DESCRIPTION

FIG. 1 is a front, top and left side perspective view of an audio system showing my new design;

FIG. 2 is a front, top and right side perspective view thereof;

FIG. 3 is a rear, top and left side perspective view thereof;

FIG. 4 is a rear, top and right side perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof;

FIG. 10 is a right side elevation view thereof;

FIG. 11 is a front, top and left side perspective view of the second embodiment thereof;

FIG. 12 is a front, top and right side perspective view of the second embodiment thereof;

FIG. 13 is a rear, top and left side perspective view of the second embodiment thereof;

FIG. 14 is a rear, top and right side perspective view of the second embodiment thereof;

FIG. 15 is a front elevation view of the second embodiment thereof;

FIG. 16 is a rear elevation view of the second embodiment thereof;

FIG. 17 is a top plan view of the second embodiment thereof;

FIG. 18 is a bottom plan view of the second embodiment thereof;

FIG. 19 is a left side elevation view of the second embodiment thereof; and,

FIG. 20 is a right side elevation view of the second embodiment thereof.

As an example of the nature and intended use of the article, the audio system may, for example, be used as a music system, an internet-connected audio system, a wirelessly-connected audio system, an audio system with television optical input, a radio receiver, a smart device-connected audio system, such as a tablet-device connected audio system or mobile-phone connected audio system, a soundbar for a television, and a soundbase for a television.

Portions of the drawings shown in broken lines represent environmental structure only and do not form a part of the claimed design. The broken line circles within the loudspeakers show that any ornamental appearance may be used for the loudspeaker surfaces, and do not form a part of the claimed design.
